(57) **CLAIM**

The ornamental design for a grooming device, as shown and described.

DESCRIPTION

FIG. 1 is a front, top, and right side perspective view of an ornamental design for a grooming device;

FIG. 2 is a front side elevation view thereof;

FIG. 3 is a rear side elevation view thereof;

FIG. 4 is a right side elevation view thereof;

FIG. 5 is a left side elevation view thereof;

FIG. 6 is a top plan view thereof;

FIG. 7 is a bottom plan view thereof; and,

FIG. 8 is a rear, bottom, and left side perspective view thereof.

The dashed broken lines in the Figures show portions of the grooming device that form no part of the claimed design.

1 Claim, 7 Drawing Sheets
